UNITED STATES PATENT OFFICE.

ERASTUS E. WINKLEY, OF LYNN, MASSACHUSETTS.

WELT-BUTTING MACHINE.

1,029,837.

Specification of Letters Patent. Patented June 18, 1912.

Application filed October 25, 1909. Serial No. 524,373.

To all whom it may concern:

Be it known that I, ERASTUS E. WINKLEY, a citizen of the United States, residing at Lynn, in the county of Essex and State of Massachusetts, have invented certain new and useful Improvements in Welt-Butting Machines; and I do hereby declare the following to be a full, clear, and exact description of the invention, such as will enable others skilled in the art to which it appertains to make and use the same.

This invention relates to machines for preparing lasted and welted boots and shoes for the sole laying operation. The operations 15 on the shoe at this time include the trimming, to proper length and form by a beveled or skiving cut, of the butt ends of the welt which, when the shoe comes from the welter, are somewhat longer than is desirable. As 20 this is an important feature of these machines the generic name, "welt butting machines" has been applied to them commercially.

In the welt butting operation the welt 25 ends are severed on a transverse line, approximately at the breast line of the heel, so that the welt will not project onto the heel seat and interfere with a proper "set" of the heel. The butted welt ends are bevelled or scarfed to provide an easy curvature to the outsole and a neat finish to this portion of the shoe.

In addition to means for butting the welt these machines may also employ means for 35 preliminarily locating the welt, relatively to the last, in proper position for the operation of the welt butting cutters, and means for securing the butted welt to the insole. It is desirable to sever any surplus inseam stitches 40 which are frequently found to extend rearwardly beyond the point where the welt is to be butted as this operation completes the severance of the butted welt end from the upper and insole and permits its immediate 45 removal from the shoe bottom after the butting operation has been performed. Another desirable operation is that of trimming off any protruding materials on the insole adjacent the butted ends of the welt to provide a smooth surface at the heel end of the 50 shoe thereby insuring an even laying of the outsole and a firm and even seat of the heel thereon.

The present invention has for its principal 55 object the provision of a welt butting machine which includes among its operating in-

strumentalities improved devices and mechanisms for performing all of the above enumerated operations.

Further objects of the invention are to 60 improve the accuracy, speed of operation and general efficiency of machines for performing the character of work referred to.

With these objects in view one feature 65 of the present invention consists in the combination in a single, organized machine of devices properly to locate the welt relatively to the insole for the welt butting and subsequent sole laying operations, cutters to butt the two welt ends uniformly relatively 70 to each other, and uniformly on all shoes of the same size, with an even and sharply defined beveled cut the rear end of which is substantially co-incident with the breast line, and a device, preferably a tacker, thereafter 75 to fasten the located and butted welt ends to the insole. Provision for cutting the surplus inseam stitches and leveling the heel seat is also made, although these features 80 of the invention are not deemed essential. Preferably the operation of the machine with respect to all of these features is automatic so that it is merely necessary for the operator to place the shoe in and remove it 85 from the machine.

In accordance with another feature of the invention the welt butting cutters are mounted in laterally movable cutter carrying heads, arranged at each side of a suitably formed shoe rest for positioning the shoe 90 bottom up, and these heads are provided with actuating means for opening and closing them independently of the operation of the coöoperating welt locating devices. This permits the welt to be located on the insole 95 preliminarily to and independently of the positioning movement of the cutters. In connection with this feature of the invention means is provided so to control the inward or cutter positioning movement of the 100 cutter carrying heads that the welt butting cutters sustained thereby are invariably placed in proper butting relation to the welt which, in turn, is maintained in proper welt butting and sole laying position relatively 105 to the insole by the welt locating devices.

A further feature of the present invention consists in the construction and arrangement of the devices for severing the inseam stitches beyond the end of the welt 110 cutting stroke of the welt butting cutters.

In the machine of the present invention

the stitch cutters are pivotally mounted on the cutter carrying heads and are normally held retracted from the shoe so as not to interfere with the operation of the welt locators. The manner in which they are mounted permits not only an inward movement into the welt crease and against the stitches but also an upward movement relatively to the insole. The former movement provides for a severance of the excess of 5 stitches and the latter movement permits the welt butting cutters to advance beneath the stitch cutters and beyond the end of the butted welt. One object of this continued 10 advance is to permit the welt fastening means to assume its operative position opposite the scarf formed at the ends of the welt by the welt butting cutters. Both of the above mentioned movements of the stitch cutters, in the preferred form of the invention, are controlled by the advance of the 15 welt butting cutters. The laterally movable cutter carrying heads in which both the welt butting and stitch cutters are mounted are held yieldingly against the sides of the 20 shoe and for this reason are somewhat easily displaced.

Another feature of the invention, therefore, contemplates the provision of a device 30 to lock the cutter carrying heads rigidly against outward movement during the operation of the cutters carried thereby, thereby insuring a proper operation of the 35 cutters on the welt and inseam.

Other features of the invention relate to 40 the construction and operation of the means for securing the butted welt to the insole, and to improvements in the construction, arrangement and mode of operation of the 45 characteristic features of this class of machines as a whole.

In the utilization of these features of the invention in their preferred form, the welt locators are advanced inwardly into light 50 contact with the sides of the shoe, and then upwardly, to a position in contact with the grain side of the welt and opposite the welt crease, by one actuating means and thereafter are forced into the welt crease, to act 55 as welt supports or cutting plates for the welt butting cutters, by another actuating means. The angle between the planes of the surfaces of the welt supports and the line of travel of the welt butting cutters provides 60 for the desired bevel or scarf on the welt ends. The second actuating means also places the welt and stitch cutters in the 65 positions, relative to the welt, which they assume preparatory to performing their offices. The welt butting cutters move longitudinally of the shoe, toward the heel, and during their operation, in one embodiment of the invention, the welt is not only smoothed out in advance of their action by 70 suitably formed pressers but the outer welt

edge at each end is engaged by a guide which assists in forcing the free welt end inwardly over the insole into proper butting position in front of the cutters. These welt edge guides, in their preferred construction and arrangement, are carried by the welt pressers. The blades forming the stitch cutters are preferably mounted upon cutting blocks having an undercut forward face which assists in securing a clean severance of the welt ends. The cutting blocks are so located that after the welt butting cutters have advanced to the end of their cutting stroke their cutting edges pass beneath the edges formed by the undercut faces. The shearing action thus obtained insures a clean cut at the welt end. It also places the welt butting cutters in a position to raise the cutting blocks and pass under them during a further advance of the said 75 cutters to a position of non-interference with the operation of devices for guiding and driving a tack into each butted welt end to secure it to the insole. The tacks are preferably inserted through the bevel just 80 formed by the welt butting cutters and, therefore, the tacker throats are mounted so as to be removable from tacking position 85 to permit the welt butting cutters to operate. Preferably, the means for bringing the 90 tacker throats into tacking position also actuates the devices for delivering tacks from the hoppers to the raceways which supply the throats.

The features of the invention hereinbefore referred to, including certain details of construction and combinations of parts as will hereinafter appear, will be further explained in the following description and then particularly pointed out in the appended claims.

The preferred embodiment of the invention is illustrated in the accompanying drawings, in which—

Figure 1 is an elevation of the left hand side of the machine showing a shoe positioned for the welt butting operation; Fig. 1^a is a detached detail of some of the actuating cams; Fig. 2 is a front elevation showing a shoe, in section, in position to have its 110 welt butted; Fig. 3 is a rear elevation; Fig. 4 is a longitudinal, vertical section on the line 4—4 of Fig. 5, the operating parts being in the same relative positions as shown in Fig. 1; Fig. 5 is a plan; Fig. 6 is a detail, in plan, showing the connection between the two laterally movable cutter carrying heads; Fig. 7 is an elevation of the right hand side of the machine showing the operative parts in the relative positions 115 which they assume prior to placing the shoe in the machine; Fig. 8 is a detail, in rear elevation, of the mechanism for locking the cutter carrying heads against outward movement after the cutters have been placed in 120 125 130

welt butting position; Fig. 9 is a detail, in plan, of the mechanism for adjusting the shoe rest; Fig. 10 is an enlarged detail, partly in section, of some of the parts shown in Fig. 4 but in the relative positions which they assume before placing the shoe in the machine; Fig. 10^a is a detail, in side elevation, of the frictional connection between the welt locator supporting arms and their actuating mechanism; Fig. 11 is a detail, in side elevation, of one of the welt locators; Fig. 12 is a front elevation of the welt locator shown in Fig. 11; Fig. 13 is a detail, in elevation and partly in section, of the inner face of the right hand cutter carrying head, together with the right hand welt locator, cutter carrying head locking device, fastener inserting mechanism, and other associated parts, the cover plate for the cutter carrying head, together with the raceway and throat plate, being broken away; Fig. 14 is a detail, similar to Fig. 13, showing the parts broken away in Fig. 13; Fig. 15 is an end elevation of the right hand cutter carrying head with the throat plate broken away; Fig. 16 is a vertical transverse section on the line 16—16 of Fig. 14; Fig. 17 is a detail, in horizontal section on the line 17—17 of Fig. 13, of the combined stitch cutter and cutting block and its operating means; Fig. 18 is a detail, in horizontal section on the line 18—18 of Fig. 13, showing also the mechanism for actuating the welt locators in plan; Fig. 19 is a detail, in front elevation, of a portion of the mechanism for actuating the welt locators; Fig. 20 is a detail, in elevation, showing the parts at the upper portion of Fig. 13, but in a position with the cam head forward and about to move back and raise the hammer; Fig. 21 is a detail, in elevation, showing the parts at the upper portion of Fig. 13, but in a position with the hammer raised and the lock for the cutter carrying heads just about to become operative; Fig. 22 is a detail of the locking device for the cutter carrying heads showing certain parts both in plan and side elevation; Fig. 23 is an elevation of the inside face of the right hand cutter carrying head having a welt presser and welt edge guide mounted thereon; Fig. 24 is a plan of the parts shown in Fig. 23; Fig. 25 is a front elevation of the parts shown in Fig. 23; Figs. 26, 27 and 28 are diagrammatic views showing the relative positions of the welt butting cutters and throat plates during the operations of butting and securing the welt. Fig. 29 is a diagrammatic view with a welt shown in section, illustrating the action of the welt presser; and Fig. 30 is a vertical section on the line 30—30 of Fig. 29.

In the embodiment of the invention illustrated in the drawings, and referring more particularly to Figs. 1, 2 and 3, the working

parts of the machine are mounted in a frame A on a base B, of suitable height. In the frame A there is journaled a driving shaft 2 extending across the machine. A driving pulley (Fig. 2) is supported on a projecting end of the shaft 2 between the frame A and a side bracket A'. Above the driving shaft 2 and also journaled in the frame A is a cam shaft 6 provided with a series of six cams, best shown in Fig. 3. These cams, reading from left to right in Fig. 3, are a groove cam C' in the face of a disk D', an edge cam C², a groove cam C³ in one face of a disk D² (in dotted lines), a groove cam C⁴ in the other face of the disk D², an edge cam C⁵ (in dotted lines), and an edge cam C⁶. At their left hand ends the driving and cam shafts are connected by gears 8 and 10 respectively, the gears being in the ratio 3:1 so that the driving shaft makes three revolutions to every single revolution of the cam shaft. This arrangement permits the driving shaft to be directly connected to the power shaft but provides ample time for the operations to be performed on the shoe. The machine is provided with a pair of forwardly projecting cutter carrying heads H and H' pivoted to swing laterally on the frame A. The machine is also provided with a pair of welt locators mounted upon swinging arms L and L'. These arms are pivoted for lateral movement in supporting frames which in turn are pivoted for vertical movement upon the cutter carrying heads H and H'. The construction and operation of these parts will be referred to in detail hereinafter. The frame A is provided with a top frame A² in which is supported a hammer D for actuating the two drivers of the fastening inserting mechanism, which coöperate with the fastening supplying mechanisms S and S' mounted on the frame A to swing laterally with the cutter carrying heads. The shoe positioning rest comprises a stand 12 formed at its upper end with a V-shaped heel socket 13 and a gage finger 14 which projects forwardly and is adapted to engage the shoe centrally of its heel seat. The stand 12 is mounted in a slide 15 (Figs. 4 and 9) which may be moved in and out, in guideways 16 carried at the base of the frame A, by moving a horizontally arranged lever 17, having one end pivoted at 18 on the frame and connected centrally, by a pin and slot connection, with the slide 15. A frame A is provided with a toothed segment 19 and the lever 17 is provided with a usual form of locking dog 20 so that the stand 12 may be locked in any position of in and out adjustment. This movement of the shoe rest is relative to the welt butting cutters and determines the distance from the heel at which the welt ends are to be butted. The driving shaft is provided with some suitable

and convenient form of one revolution clutch, preferably located inside the pulley 4, but as the clutch forms no part of the present invention it will not be described in detail herein. It is desirable, however, to refer briefly to the controlling device for the clutch because of the selected speed ratio between the driving and cam shafts.

Referring now to Figs. 2, 4 and 7, the 10 clutch, of whatever type it may be, is thrown in and the machine is set in operation by depressing a treadle (not shown) connected to a treadle rod 21 (Fig. 4). This breaks the toggle 23 and lowers the brake shoe 24 about its pivot, thus removing it from its operative position. Pivoted centrally at 25 in the frame A is a lever 26 having one end connected by a link 27 to the knuckle of the toggle 23 and having at its other end a roll 28 which engages the edge cam C² (Fig. 3). This cam is of such design (see dotted lines Fig. 7) that after the clutch has been thrown into operation by breaking the toggle 23, it will, by its control of the lever 26, maintain 20 said toggle broken during three revolutions of the driving shaft, or until the cam shaft has completed one full revolution. After a single revolution of the cam shaft has been completed, the roll 28 reaches a position (see 30 Fig. 7) on the cam C² where the spring of the treadle (not shown) for straightening the toggle 23 may act to move the roll inward and thus permit the toggle to be straightened.

35 The preferred form of the invention may be described briefly as including among its features a pair of combined welt butting and heel seat leveling cutters arranged above the welt and movable longitudinally of the shoe, a pair of welt locating and supporting devices which comprise plates or fingers adapted to be placed against the underside of the welt and forced into the welt crease, a pair of combined stitch cutters and cutting blocks, and a pair of tackers for driving tacks into the butted ends of the welt. These features of the invention provide for simultaneously locating and supporting the welt ends in proper butting position relative to 40 the path of travel of the welt butting cutters, insures a clean and square severance of the welt ends, prepares the heel seat for the reception of the outsole, completely severs the butted welt ends from their connection with the upper and insole, and finally, secures the butted welt ends in their sole laying position, in which they have been placed 45 prior to the butting operation.

Owing to the location of the channel guide 60 just forward of the needle in the welter, it is impossible for the operator when attaching the welt to continue the line of stitches up to the forward heel seat tacks. There is, therefore, an unsecured portion of the upper 65 between the end of the inseam and the for-

ward heel seat tacks and this portion of the upper is not only loose on the last but ordinarily is drawn outwardly away from the last by the highly tensioned portions of the quarter at each side of these points. The 70 end of the welt which has been attached to this portion of the upper by the welter is also drawn outwardly from the last by the tension on the upper at this point. This, then, is the usual position of the welt ends when the shoe is brought to the machine. If the shoe were placed in the machine and the welt were butted by a longitudinally moving knife while the ends remained in this position, the cut would not be made 75 square across the welt and a portion of the butted welt would project onto the heel seat which is undesirable. Means is provided, therefore, to properly position the welt with relation to the cutters prior to the butting 80 operation by forcing its end inward over the insole preferably through an engagement with the inseam at the point where the upper has been drawn outwardly from the last.

The form and arrangement of the welt 90 locators, adopted for the illustrated embodiment of the invention, is best shown in Figs. 2, 10, 13, 18 and 19. As heretofore mentioned, they are mounted upon laterally swinging arms L and L' which in turn are 95 mounted in frames sustained by the cutter carrying heads H and H'. As the form and arrangement of the welt locator at each side of the shoe is the same, it will suffice to describe but one of them. Referring now 100 more particularly to Figs. 10 and 13, the right hand welt locator arm L' is segment-shaped and carries at its upper end the welt locator proper 30. The welt locator 30 is adjusted angularly upon its arm L' in a 105 manner and for a purpose to be presently described. The arm L' is fulcrumed upon a vertically arranged pivot 32 carried by a frame 34, capable of a vertical movement about a horizontally arranged pivot 36 carried in an ear 38 depending from the cutter carrying head H'. The welt locator arm L' is provided with an inwardly projecting web 40 through which there is passed a pin 42, having threaded thereon a collar 44 provided with a rounded face adapted to bear in a socket formed in the rear side of the web. In front of the web the pin 42 is provided with a coiled spring 46, its inner end bearing upon a collar 48 loose on the pin and having a rounded face adapted to bear in a socket in the forward side of the web, and its outer end bearing upon a pair of lock nuts 50 threaded on the pin. With this construction the pin 42 may be drawn rearward 115 through the web 40 against the force of the spring 46 but cannot be moved forward relatively to said web. The rear end of the pin 42 is provided with a ball (Fig. 10) which is held by a screw plug 51, in a socket in the 120

125 130

upper end of a crank 52 pinned to and projecting upwardly from a rock shaft 54 extending across the machine and journaled in the sides of the frame A. At its right hand end the rock shaft 54 has pinned thereto a second upwardly projecting crank 56 having at its upper end a cam roll 57 (Fig. 2) which engages the groove cam C' in the cam disk D'. Adjacent the inner side of the hub of the crank arm 52 and between this crank arm and the corresponding crank arm 52 for the head H, is the hub of a lever 58 which depends from the rock shaft 54. This lever is loose on the rock shaft and its lower end is connected by a link 60 to the knuckle of a vertically arranged toggle formed of lower and upper links 61 and 62 respectively. The lower link 61 has its outer end pivoted to a lug 63 rigidly secured to the base of the frame A. The upper link 62 of the toggle has its outer end pivotally connected to one arm 64 of a double armed lever mounted loosely upon the rock shaft 54 outside of the crank arm 52. The other arm 66 of the double armed lever is provided with a bearing plate 68 having a rounded surface upon which the base of the frame 34 carrying the welt locator support L' rests and slides. The bearing plate 68 may be adjusted vertically relatively to the end of the arm 66 by means of an adjusting screw and lock nut 69, guide pins 70 being provided to prevent its rotation.

The hubs of the crank arm 52 and the lever 58 are cut away at their adjacent faces in a manner to form interlocking shoulders 71 and 72 respectively similar to the shoulders on the ordinary form of dovetail clutch (see Fig. 19) but in the present instance these shoulders are so formed that there is provided a certain amount of loose play between them (see Figs. 10 and 19). The depending lever 58, being located at the center of the rock shaft 54, may be utilized to operate both of the welt locator arms and, therefore, it is provided with shoulders 72 at each side. Similarly the link 60 may, and does, have its lower end forked and is thus connected to the operating toggles for both of the welt locator arms. An actuation of the central depending lever 58 will, therefore, communicate motion to both of the welt locator supporting arms L and L' in a manner to be now described. At the time a shoe is being placed in position against the heel socket 13 and heel seat gage 14 of the shoe rest and before the clutch has been thrown in by depressing the operating treadle, the welt locators are held by the groove cam C' in a position below the welt, as shown in Fig. 10. They are also swung outwardly at this time to a position removed from the sides of the shoe owing to their being mounted upon the cutter carrying heads, which, before the shoe is placed in the machine, also

are in their outward locations. A rotation of the groove cam C' immediately imparts a rotary movement to the rock shaft 54. This imparts a movement backward, or to the left in Fig. 10, to the crank arm 52. The depending lever 58 remains idle during the first portion of the backward movement of the crank arm 52 because the relative positions of this lever and crank arm at this time are such that the shoulders 71 and 72 between their hubs are separated. The initial rotary movement imparted to the rock shaft 54 merely closes the gap between these two set of shoulders so far as the depending lever 58 is concerned. During the time that this gap between the shoulders 71 and 72 is being closed, however, the backward movement of the crank arm 52 exerts an inward pull upon the pin 42. The pull on this pin acts to move the welt locator supporting arm L' inward about its pivot 32. This arm will continue to move inward under the action of the cam C' until the welt locator 30 engages the counter of the shoe. At this time the vertical position of the welt locator still remains as shown in Fig. 10, that is, below and out of contact with the under or grain side of the welt. By the time that, or soon after, the welt locator has engaged the counter of the shoe, the shoulders 71 engage the shoulders 72 and a continued movement to the rear of the crank arm 52 will now cause a forward rotation of the depending lever 58 about the rock shaft 54 as a center. After the welt locator 30 has engaged the counter of the shoe, the further throw of the cam C' is taken up by a compression of the spring 46. The compression of this spring acts to hold the welt locator against the counter of the shoe but as this spring is a light one the pressure is not great.

It is sometimes found convenient to supplement the action of the spring 46 by the additional pressure exerted by a spring 33 coiled around the pivot pin 32 and secured in a manner to exert an inward pressure upon the welt locator arm. The spring 33, however, is not essential to the operation of the welt locators. The forward movement of the depending lever 58, caused by the continued rotation of the rock shaft under the action of the cam C', causes its lower end to move to the right in Fig. 10 until it assumes the position shown in Fig. 13, at which time the toggle 61, 62 has been straightened. The straightening of the toggle raises the arm 64 of the double arm lever mounted loosely upon the rock shaft 54 outside of the crank arm 52. The arm 66 of this lever, rising in unison with the arm 64, forces the frame 34, which it supports and which carries the welt locator, upward about the pivot pin 36. During this upward movement the welt locator is continuously pressed against the counter of the shoe by the spring 46, al-

though it will be understood that the pressure is not sufficient to mar the upper. The upward movement continues under the straightening action of the toggle until the 5 welt locator passes over the rounded portion of the last adjacent the breast line of the heel and engages the under or grain side of the welt. The welt locator is formed with an 10 inwardly projecting stitch engaging blade 29 and a cut-away under surface 31 (see Fig. 12) so that at this time the blade 29 is in a position opposite the welt crease and ready 15 to be forced into the welt crease into contact with the inseam stitches. An inward pressure on the welt locator will, therefore, 20 cause a tightening and stretching of the upper at this portion of the shoe and force the end of the welt inwardly over the insole into position to be butted by the welt butting 25 cutter. The spring 46 is, however, too weak, even when supplemented by the spring 33, to perform this function. In the preferred embodiment of the invention the movement 30 of the welt locators into the welt crease at each side of the shoe is accomplished by means other than the means which place the locators in their positions opposite the welt crease. As illustrated, the required inward 35 pressure upon the welt locators is secured from the inward movement of the cutter carrying heads H and H' as this provides for an equal inward movement of the welt locators and welt cutters and preserves their relative working positions.

35 Referring now to Figs. 10 and 15, each of the cutter carrying heads is provided at its outer side with a depending lug 80 in the form of a hook and having its inner surface beveled as at 81. Each of the welt locators 40 30 is provided with a rearward projection 82 having its underside beveled as at 83, Fig. 12. As the cutter carrying heads are moved inward by means presently to be described, the beveled surfaces 81 and 83 engage 45 each other before the heads have reached their final position with the welt butting knives in welt butting position above the ends of the welt and thereafter the welt locators 30 are carried inward with the 50 heads, the knives and locators being at this time in the desired relation for proper operation on the welt. The preliminary adjustment of the bearing plate 68, of the double armed lever mounted upon the rock 55 shaft 54, has been such that the under or grain side of the welt opposite the center of the blade 29 of the welt locator has been raised just to a position in the plane of cut of the welt butting cutter. This plane of 60 cut is in the plane of the bottom of the cutter carrying heads. If, however, during the operation of the machine, this adjustment is negated by wear of parts or any other cause, the wedging action of the bevel-

ed surfaces 81 and 83 upon the parts 80 65 and 82 will lift the welt locators 30 about their pivots 36 and bring them into contact with the undersides of the cutter carrying heads thus determining a proper vertical 70 location of the center of the welt locator 75 blade 29.

Referring now more particularly to Figs. 1, 2, 5, 6, 13, 15, and 16, the construction and operation of the cutter carrying heads will be described. The cutter carrying 75 heads proper comprise the channel shaped members H and H', already referred to, (see Fig. 16), which at their rear ends are provided with bearings pinned to a vertically 80 arranged stud 84 rotatably mounted in journals 86 upon the frame A. Each of these heads sustains a casting 88, which in turn supports a hopper 90 for receiving tacks, a guideway for a tack driver 92, and a race-way 94 for supplying tacks in a position to 85 be driven by the driver through a throat plate 96 also sustained by the casting. Those parts will be described more in detail 90 hereinafter. Each of the castings 88 is pivoted at their rear ends upon vertical pins 98 (Figs. 4, 5 and 6) which are journaled at 95 their upper ends in a web A³ (Fig. 5) extending across the top of the hammer supporting frame A² and at their lower ends in lugs A⁴ (Fig. 6) extending inwardly from 100 the sides of the frame A. The castings 88 project downwardly over the inner sides of the cutter carrying heads H and H' and form cover plates 100 (Figs. 14 and 16), which partially close the opening in the 105 sides of these heads. Each casting 88 is connected to its cutter carrying head so that the heads and frames move in unison about their vertical pivot pins by means of a bolt 102 (Fig. 7) which is passed through bosses 105 extending from the outside faces of the 110 cutter head and tack hopper. A screw 103 (Fig. 14) securing the cover plate 100 to its cutter carrying head also assists in holding 115 these parts together. Each of the tack 110 hoppers 90 is provided at its back with a web which has formed thereon a toothed segment 104, the teeth of which mesh with 120 each other. One of the hoppers, as shown 125 the right hand hopper in Fig. 6, is provided with an inwardly extended crank 106 and the end of this crank is connected, by a universally connected link 108, to the upper end of a lever 110 (Figs. 3 and 13), which is pivoted upon a stud 112 projecting from a boss 113 on the inner face of the left hand side of the frame A. The lower end of the lever 110 is provided with a cam roll 114 which bears upon the peripheral cam C⁵ (Figs. 1, 1^a and 3). The vertical web 89 of each of the castings 88 is provided with an opening near its top and a rod 116 is passed through this opening and is provided on

each end with a coiled spring 118 held in position against the web by nuts 119 threaded on the ends of the rod.

With the construction just described, 5 when the machine is at rest the riser of the cam C⁵ is beneath the cam roll 114 and the cutter carrying heads H and H' are held apart by means of the forward pressure exerted by the upper portion of the lever 110 10 upon the crank 106. At this time the springs 118 are held under compression on the rod 116. When the cam shaft has revolved sufficiently to withdraw the riser of the cam C⁵ from beneath the cam roll 114, 15 the springs 118 are permitted to expand and thus exert an inward pressure upon the vertical webs of the castings 88 and through this pressure move the cutter carrying heads inward. The springs 118 are of considerable strength although they must not be 20 of greater strength than the inseam on the shoe in order to avoid injury to the shoe. It is the action of these springs which causes the lugs 80 on the outer faces of the cutter 25 carrying heads to engage the projections 82 upon the welt locators, and by means of the inward movement of the heads force the welt locators into the welt crease and against the inseam, thus tightening the upper 30 at the breast line of the heel and forcing the welt in over the insole in proper position to be squarely and evenly butted.

The construction and arrangement of the cutters within the cutter carrying heads are 35 best shown in Figs. 10, 13 and 16, and the diagrammatic views. As the construction, arrangement and operation of these cutters is the same on both sides of the machine, it will suffice to describe but one of them. Referring now to Fig. 16, the inner vertical 40 surface or web of the channel shaped cutter carrying head H' is provided with a guide-way h' which directs the movement of a channel shaped welt butting cutter actuator 45 120 constructed to slide thereon. This actuator, at the forward end of its upper side, is provided with a head 119^a having an under or inner beveled surface 122 (Figs. 10 and 13). The lower side 121 does not project 50 as far forward as the upper side and terminates in a forward bevel 123. Its upper or inner surface forms a shelf 124 (Fig. 16). The under side of the channel shaped head H' does not extend forwardly beyond 55 the shoulder h² (Figs. 7 and 10) and, therefore, forward of this point the under surface of the lower side of 121 of the actuator is flush with the bottom surface of the cutter carrying head. The vertical web of the actuator 60 is provided with a longitudinal slot 125 (see dotted lines Fig. 10) and through this slot there projects a pin 126 which is threaded into the web of the cutter carrying head (see Fig. 16). The head of this pin 65 projects inwardly through a longitudinal

slot 127 formed in the freely movable carrier 128 which supports at its forward end the welt butting cutter 130 (Figs. 10 and 15). This cutter comprises a transversely arranged blade, sharpened at its rear edge. 70 This blade projects inwardly from its carrier beyond the cover plate for the inner face of the cutter carrying head over the insole of the shoe, when the head is in its inner position. The knife is held in place 75 upon its carrier by means of a block 129 (Fig. 15), suitably secured to the forward end of the carrier. A pin 131 (Fig. 10) depends from the rear end of the cutter carrier and is connected by a coiled spring 132 with a second pin 133 (Figs. 7 and 15) carried by the cutter carrying head. This spring is normally under tension and maintains the cutter carrier 128 turned about its pivot 126 in the position shown in Fig. 10. 80 The welt butting cutter actuator 120 is connected by means of a universal link 134 (Figs. 4 and 13) with the upper end of a cam lever 136 pivoted at its lower end upon a stud 138 (see dotted lines Fig. 3) extending 85 across the frame A at the rear of the machine. The lever 136 is a double lever (see Fig. 3) and at its upper end is connected by similar links 134 to the actuators in both of the cutter carrying heads. The lever 136 is provided between its ends with a cam roll 137 (Fig. 1^a) which is engaged by the groove cam C⁴ in the right hand face (viewing Fig. 3) of the cam disk D² on the cam shaft 6. 90

After the cutter carrying heads have been moved inward into the position already described and the welt ends have been moved inward over the insole by the welt locators so that they lie longitudinally of the shoe 105 and in the line of travel of the welt butting cutters, the cam C⁴ operates to move the cam lever 136 to the rear (Fig. 4), which movement draws the welt butting cutter actuators 120 rearwardly within the cutter carrying heads. The first effect of this rearward movement of the actuators, upon the cutter carriers 128, is to swing them downward about their pivot pins 126 by reason 110 of the engagement of the bevel surfaces 122 on the heads 121 of the actuators with complementary bevel surfaces at the upper side of the forward ends of the cutter carriers. The welt butting cutters 130 are moved downward in this manner until their cutting edges are in the plane of the bottom of the cutter carrying heads, that is, in the plane of the central portion of the welt locator blades 29. The relative location of the parts just described is best shown, diagrammatically, in Fig. 26. When the cutter carriers have been placed in this position, in addition to the engagement between the bevel surfaces at the forward ends of the actuators and the cutter carriers, these parts 115 120 125 130

are also held together by an engagement of the lower faces of the carriers with the shelves 124 of their respective actuators (see Fig. 27) and by an engagement of shoulders 135 at the rear ends of the carriers with ribs 1371 on the upper sides of the actuators (see Fig. 13). Thus the cutter carriers are firmly locked by a three-point contact to their actuators and the actuators in their continued rearward movement are thus enabled to draw the cutter carriers with them. The continued rearward movement of the welt butting cutter actuators, under the action of the cam C⁴, provides for the cutting stroke of the welt butting cutters. The plane of cut is in the plane of the bottom faces of the cutter carrying heads, but as the welt ends have been placed in contact with the slanting upper surfaces of the welt locators at the time the welt butting cutters are moved downward into a position to start the cut, the welt now lies at an angle to the line of travel of the cutter (see Fig. 27) and, therefore, the welt will be beveled as its end is severed by the cutter (see Fig. 28).

The angle of the bevel upon the welt end is determined by the adjustment of the welt locators 30 hereinbefore mentioned. Each of the welt locators is mounted for angular adjustment upon the end of its supporting arm. To this end each of the welt locators is provided with a circular groove 140 (Fig. 11) within which there fits a circular tongue 141 (Fig. 12) upon the inner side of the upper end of its supporting arm. These circles in each case are struck from a center at the central point of the surface of the welt locator blade 29 and, therefore, the welt locators may be swung in these arcs and vary the angle between their welt supporting faces and the plane of the bottoms of the cutter carrying heads without disturbing the vertical relation of the central point of the welt locator blades to said planes. Each of the welt locators 30 is held in any position of angular adjustment by means of a set screw 142. With this construction if a long scarf, or bevel, is desired upon the end 50 of the welt, as is requisite for some styles of shoes, the upper face of each of the welt locators is adjusted upon its tongue 141 until it is almost parallel to the plane of the bottom of its respective cutter carrying head, while on the other hand if a sharper bevel is desired the angle between the two surfaces mentioned is increased by a proper angular adjustment of the locator head. No matter, however, what the angular adjustment of the welt locators, the welt is always forced into contact with their upper surfaces prior to any cutting action by the welt butting cutters. Means is provided to adjust the stroke of the welt butting cutters 65 so that it is completed when the cutting edges

of the knives reach the central point of the welt locating blades 29, that is, just at the time that the knives emerge from the under or grain side of the welt (see dotted lines Fig. 27). The distance of the point at which the welt is butted from the heel of the shoe may, therefore, always be maintained constant no matter what the angle of the bevel is. The length of stroke of the welt butting cutters may be determined by an adjustment of a turnbuckle 143 (Fig. 4) formed on each of the links 134 which connect the welt butting cutter actuators 120 with their double cam lever 136.

It will be noted that the projecting blades or fingers 29 of the welt locators act as welt supports for supporting the welt in a horizontal plane, thus providing for a square cut across the welt ends by the welt butting cutter. If the welt were held in a plane at an angle relatively to the plane of cut of the welt butting cutters, the severance of the welt end would be upon a diagonal line which is undesirable as, for the best work, no portion of the butted welt should extend onto the heel seat. On the contrary the welt should be severed along the line corresponding to the breast line of the heel. If the welt should be in temper at the time the welt butting operation is performed, which is ordinarily the case, or should be formed of stringy stock, it is difficult to sever its ends with a clean cut notwithstanding the fact that the welt supporting surfaces of the welt locators act as cutting plates for the knives. In order to insure at all times a clean severance of the welt end, in the preferred embodiment of the invention, a cutting block is provided which is placed just at the end of the stroke of the welt butting cutter and is so formed that as the cutter emerges from the under, or grain side, of the welt the cutter and cutting block act together as shear blades to effect a severance.

The location, construction and operation of the cutting block is best shown in Figs. 10, 13, 16, 17 and 18. As these blocks are the same for both of the welt butting cutters, a description of one will suffice for both. Referring first to Figs. 17 and 18 the depending ear 38 on the cutter carrying head H' is provided with a pair of inwardly projecting bosses in which there is journaled a vertically arranged stud 144. On this stud there is pivoted, for a lateral swinging movement, a block 146 which block carries a horizontally arranged stud 148. On the stud 148 there is pivoted a cutting block carrier 150, carrying at its forward end the cutting block 152. The swinging block 146 is provided with a rearwardly extending lug 154 and between this lug and the ear 38 there is seated, in any convenient manner, a horizontal coiled spring 156 normally under compression and oper-

ating to move the lug inwardly about the pivot 144 as a center. This maintains the cutting block 152 within a recess 158 (Figs. 16 and 18) formed for its reception in the 5 under side of the lower portion of the welt butting cutter actuator 120. The parts are so mounted that when in the recess 158 the under side of the cutting block is in the plane of the bottom of the cutter carrying 10 head, that is, in the plane of the bottom of the lower side 121 of the welt cutter actuator (see Fig. 10). A spring 160 (Fig. 10) is mounted in a manner to exert a downward pressure upon the carrier 150 turning 15 it about its pivot pin 148 and maintaining a lug 161, projecting rearwardly from the carrier in contact with the underside of a lug 162 projecting from the side of the block 146. When under control of the 20 springs 156 and 160 the cutting block carrier 150 is maintained in a position within the recess 158 and in the horizontal plane referred to. It is in this position at the time the cutter carrying head is in its inner position with its welt butting cutter over the 25 welt and in position to be moved down against the welt. It is, therefore, at this time in a position removed laterally from the welt but opposite the welt crease. The 30 cutting block carrier 150 is provided, at its upper side, with an anti-friction roll 164 (Figs. 16 and 17) and the welt butting cutter actuator 120 has secured thereto a cam plate 166 which, as the actuator is drawn 35 backward within the cutter carrying head, engages the roll 164 and acts to swing the carrier 150 about its vertical pivot 144 and move the cutting block 152 laterally toward the shoe and force it into the welt crease. 40 As no particular attention is paid to the point at which the inseam stitching operation is stopped, it frequently happens that the inseam stitches extend beyond the point where it is desired to butt the welt. The 45 support for the welt secured from the welt locators extends only to the inseam and in order that the severance of the welt may be clean across its entire width, it is desirable that the cutting block be moved inwardly 50 far enough to extend beneath the entire width of the welt. If the inseam stitches extend beyond the point at which it is desired to butt the welt they will effectually prevent such a location of the cutting block 55 unless they are severed. To provide for a severance of these stitches the inner edge 168 (Fig. 17) of the cutting block is sharpened and the block thus acts as a stitch cutter when it is forced inward by the action of 60 the cam plate 166. The cutting block is thus enabled to assume its most effective position beneath the welt. The severance of the stitches referred to also assists in the welt butting operation, as if these stitches 65 were not severed it would be impossible to

remove the butted end of the welt from the shoe after it has been beveled by the welt butting cutter.

A clean and sharply defined cut of stock in temper, or otherwise difficult to handle, is secured by making the cutting block in the form shown most clearly in Figs. 25 to 27. As there illustrated the forward side of the combined cutting block and stitch cutter is beveled so that the welt end is supported 70 thereon at an angle and this forward side is furthermore provided with a slightly undercut portion 170 forming an edged shoulder beneath which the cutting edge of the welt butting cutter may be thrust at the end of 80 its stroke. The relative position of the cutting block 152 and its respective welt locator 30 is such that the shoulder formed by the undercut portion is directly above the central portion of the welt locator blade 29, 85 or in other words, just at the end of the stroke of the welt butting cutter. The co-operation of these parts, in effecting a clean severance of the welt, is as follows. By the time that the welt butting cutter is brought 90 to the position shown in Fig. 26, by its actuator 120, the cam plate 166 has been moved rearwardly a sufficient distance to force the combined stitch cutter and cutting block 152 inwardly beneath the welt and 95 against the inseam. Any stitches which may be in the rear of the point at which it is desired to butt the welt are severed by the stitch cutter, the cutting block is placed beneath the welt, its shoulder 170 assuming 100 a position just above the central point of the welt locator blade 29. As the welt butting cutter is drawn within the cutter carrying head, under the further inward movement of its actuator, it bevels the end of 105 the welt and finally, just as it completes its stroke and emerges from the welt, travels beneath the shoulder 170. The upper edge of the shoulder and the knife thus act together as shear blades to cause a clean and 110 sharply defined severance of the welt ends. As heretofore described, each of the cutter carrying heads is provided with its individual hopper, raceway, driver and throat plate, but a single hammer is used to operate both of the drivers. The construction and operation of the single hammer D for the two drivers is best illustrated in Figs. 4, 5, 7 and 13. Each of the drivers 92 at its head is provided with a rearwardly projecting ear 172 (Figs. 4 and 13) which is engaged at its under side by a bail 174 on the hammer. The bail is provided with a rearwardly projecting lug connected by a screw 175 (dotted lines in Fig. 13) to the 120 underside of the front end of the forepart 176 of the hammer which is made in two parts for a purpose presently to be explained. The forepart 176 of the hammer is provided with a T-shaped head 178 (Fig. 130

5) which bears upon the upper ends of the two drivers 92. The bail 174 is secured, by screws 179, to the upper side of the head 178. With this construction the drivers 92 are moved positively in both directions as the forepart 176 of the hammer moves up and down. The forepart 176 is permitted a vertical, oscillatory movement by being loosely pivoted, at its rear end, upon a transverse stud 180 carried by the hammer frame A². Loosely pivoted on the same stud, but by its forward end, is the rear part 182 of the hammer. These two parts engage each other through the intervention of lugs 184 and 186 on the forepart and rear part respectively (see Fig. 7). The drivers 92 are normally maintained in their lowermost or driving positions by means of a torsion spring 188 (Fig. 5) which is coiled around the stud 180. One end of this spring bears downwardly upon a lug 189 on the forepart 176 and its other end is held against movement by a suitable connection to the hammer frame A². The connection to the hammer frame is through an adjustable screw 190 (Fig. 3), carried in a bracket 191 upon the hammer frame, by means of which the tension of the torsion spring may be varied.

30 In the operation of the drivers 92, the two-part hammer is oscillated against the force of the spring 188, by means now to be described, which at a predetermined time act to suddenly release the hammer and permit the drivers to be moved downward through the throat plates 96 under the expansive force of the spring 188 which, therefore, acts as a driving spring. The rear part 182 of the hammer is provided at its rear end with an anti-friction roll 183 which is adapted to be engaged by a cam head 192 (Fig. 4) on the upper, bent arm 194 of a bell-crank lever loosely pivoted upon a stud 196 mounted in the hammer frame A² below and to the rear of the stud 180. To the lower arm 198 of this bell-crank lever there is pivoted the upper end of a pitman 200 having at its lower end a slot through which the cam shaft passes, and intermediate its ends 45 a cam roll 202 which engages the groove cam C³ in the lefthand face (viewing Fig. 3) of the cam disk D². A rotation of the cam C³ oscillates the hammer B in the following manner. As the pitman 200 rises it turns the arm 194 of the bell-crank in a direction to move the cam head 192 forward. The forward movement of this head causes its upper cam surface 191 to engage the anti-friction roll 183. The formation of 50 the cam surface is such that the rear part 182 is lifted as the cam head is moved forward, such a lifting being permitted by the connection between the forepart and rear part, the lug 186 separating from the lug 184. After the cam C³ has advanced the

cam head 192 to a position where it is wholly in front of the anti-friction roll 183 (see Fig. 20), its forward motion ceases. The cam C³ now acts to move the cam head 192 rearward but as the rear part of the hammer has by this time again descended, the cam head 192 during this first part of its movement engages the anti-friction roll 183 with its under cam surface 193, thus riding over the anti-friction roll on its backward stroke. As the cam head moves backward the rear part of the hammer is slowly lowered, thus raising the forepart of the hammer because of the formation of the lug connection between the two parts, against the force of the driving spring 188. The upward movement of the forepart of the hammer about its pivot 180 continues until the cam head 192 has reached a position where a slight further backward movement will move it off of the anti-friction roll 183 and permit the hammer to be actuated by the driving spring (see Fig. 21). The cam head 192, however, is retained in this position by a dwell in the cam C³ which 70 retains control of the hammer during the time that the cutter carrying heads are being moved toward the shoe and the welt is being located for the butting knives and thereafter butted. It will be noted (see 75 Fig. 5) that the bail 174 at each side of the hammer head is given a slight curvature about the vertical studs 98, which form the pivots for the cutter carrying heads, as centers. This permits the cutter carrying 80 heads, which sustain the drivers 92, to be moved toward and from the shoe freely without disturbing the relation of the hammer to the drivers.

Referring now to Fig. 14, each of the 85 hoppers 90 is provided with a rotary picker plate 204, of well known construction, secured to a rock shaft 206 passed centrally through the hopper. These picker plates are given an intermittent rotary motion so 90 as to pick up tacks and deliver them to the raceways 94, in a manner well known to those skilled in the art, by an actuating mechanism presently to be described. The raceways 94 are of any usual or convenient 95 type being provided at their lower ends with spring pressed separator plates 208 which are removed from the opening of the raceway by an actuating finger carried by the driver. These parts may be, and preferably 100 are, all substantially as shown and described in the patent to Crisp *et al.*, No. 500,225. Each of the throat plates 96 is mounted upon a carrier 210, which is of the shape 105 best shown in Fig. 7, and is provided with a forked upper end, straddling the casing for its driver 92 and pinned to a transverse rock shaft 212 (see dotted lines Fig. 15) mounted in the casting 88 on top of the cutter carrying head. Each of the rock shafts 110

212 is provided at its outer end with a rearwardly projecting crank arm 214 (Fig. 7). Each of the crank arms 214 is connected by a link 216 (see dotted lines Fig. 13) with a sliding collar 218 mounted upon lower extensions of the studs 84 upon which the cutter carrying heads are pivoted. Each of the sleeves 218 is provided at its lower end with a pair of collars which engage anti-friction rolls within the forked forward ends of levers 220 which are pinned to the transverse rock shaft 138 at the rear of the machine. This shaft is rocked by means of the edge cam C⁶ which engages a roll 222 (Figs. 1^a and 3) within a yoke at the upper end of a vertically arranged crank arm 224 which rises from the hub of the right hand lever 220 (viewing Fig. 3). The sleeves 218 are each prevented from rotation upon the 20 studs 84 by being guided on pins 225 secured to said studs. With this construction the links 216 and their connected sleeves 218 are permitted to rotate with the studs 84 within the forked ends of the levers 220 as the cutter carrying heads and attached throat plates are moved toward and from the shoe. When the sleeves 218 are in their lowermost position, as shown in Fig. 10, the throat plates are raised, as shown in that figure 30 and in Fig. 7, but when the sleeves 218 are in their upper positions on the extensions of the studs 84, as shown in Fig. 13, the throat plates assume the position shown in Figs. 4 and 14, that is, with their tack passages directly beneath and in the line of movement of the drivers 92.

It is important that in securing the butted welt end to the insole the fastening devices be inserted through that portion of the welt that has just been operated upon by the welt butting cutter, that is, through its beveled end, because this is the point which lies just forward of the foremost heel seat tack and in the rear of the last inseam 40 stitches where there is no fastener to hold the upper in place. By securing the welt to the insole at this point a two-fold purpose is accomplished, that is, the welt is secured in place in the position in which it is held by the welt locators, and the upper, which has been tightened over the last by the action of the welt locators, is also secured in place while so held. The forward ends of the shoe counter are generally of such length 50 that they project to a position slightly forward of the breast line and, therefore, beneath the end of the butted welt. If the ends of the counter have been upturned by the channel guide of the welter, as is frequently 55 the case, they will be laid flat to the insole by the fastener which secures the butted welt end in place. Thus a securing of the welt end will lay all the materials flat to the insole at this point and will, in addition, last 60 the upper. These advantages do not obtain where the tack or other securing means is driven into the welt at a point forward of the end of the inseam, as the upper is already snugly held to the last at this point and there are no projecting parts which 70

The mounting of the throat plates 96, in the manner just described, is designed to provide for an insertion of the securing tack through the bevel of the butted welt, or that portion of the welt which has just been operated upon by the welt butting cutter. During the time that the throat plates are removed from their position beneath the tack drivers, as shown in Fig. 10, the welt 75 butting cutters are enabled to operate. If, however, they stop at the actual end of their cutting stroke, in the position shown in dotted lines in Fig. 27, they would then be just beneath the drivers and, therefore, in 80 the way of the throat plates when they are brought to tacking positions as shown in Fig. 28. In order to permit the throat plates to be placed in tacking position beneath the drivers, the cam C⁴ is so designed that the 85 welt butting cutters are given a stroke in excess of what is required to butt the welt, that is, they are drawn backward until they are in the rear of the center of the welt locators, as shown in Fig. 28. They are permitted to thus travel farther backward beyond the cutting blocks 152 owing to the mounting of the cutting blocks upon the transverse pivot pins 148. During this excess movement the cutting blocks merely 90 ride up over the rear faces of the welt butting cutters (see Figs. 13 and 28) being moved against the force of the springs 160. The extra travel imparted the welt butting cutters, as illustrated, is just sufficient to 95 permit the throat plates to assume the position shown in Fig. 28 directly over the rear end of the scar made on the welt by the welt butting cutters, but obviously the amount of excess travel may be varied 100 widely. Just at the time that the throat plates have reached tacking position the cam head 192, which up to this time has been at rest and holding the hammer D raised, is moved backward sufficiently to release the 105 hammer and permit its driving spring to force the drivers downward, thus separating a tack from the raceway and driving it through the throat plate to secure the end of the welt to the insole. 110

The intermittent rotary motion of the picker plates 204 within the hoppers is, in the illustrated embodiment of the invention, obtained from the oscillatory movement of the crank arms 214. Each of these 115 arms is provided at its rear end with a toothed segment 226 (Fig. 1) which meshes with a usual form of slip gear 228 on the outer ends of each of the shafts 206. The slip gear is so mounted that upon each down- 120

ward movement of the link 216, under the action of the cam C⁶, the picker plate is rotated through a half revolution, to a position as shown in dotted lines in Fig. 13, and 5 is maintained in this position during the upward stroke of the link, which gives time for the tacks on the picker plates to slide therefrom and into the raceways 94.

In order to prepare the heel seat for the 10 reception of the outsole, it is desirable that all protruding substances, such, for instance, as the rear ends of the channel flap, be removed from the insole. This will provide a smooth surface upon which the outsole 15 can be laid, making an even seat for the reception of the heel. As the shoe has been operated upon by the inseam trimmer prior to the welt butting operation, generally speaking, the only materials protruding 20 from the heel seat will be those portions of the channel flaps which are in the rear of the butted end of the welt and the upper and lining and other parts within the upper in front of the heel seat tacks. The continued 25 backward movement of the welt butting knives, heretofore described, may very conveniently be used to perform the heel seat leveling operation. In the preferred embodiment of the invention the throw of the 30 cam C⁴ is such as to cause the welt butting knives to move rearwardly beyond the center of the welt locators for about one-half an inch which will carry their cutting edges substantially to the foremost of the heel 35 seat tacks. This throw will, of course, be preliminarily adjusted, by means of the turn buckles 143 (Fig. 4), so that all protruding materials at the heel seat will be severed from the shoe and the seat will be effectu- 40 ally leveled, but, at the same time, the knives will be kept from contact with the heel seat tacks, which would dull them. With the welt butting cutters operating as described, the welt is not only cleanly and 45 squarely cut with the desired bevel at its rear ends, but all inseam stitches beyond the end of the butted welt are severed and the butted welt end, together with all materials protruding from the heel seat at the sides of 50 the shoe in front of the heel seat tacks, are completely removed from the insole. After the welt has been butted and secured in place with the machine of the present invention, the heel seat of the shoe is ready for 55 the sole laying operation without the necessity of any further operations upon it.

As heretofore described, the cutter carrying heads are drawn to their inward position with the knives in proper relation to 60 the welt to perform their offices by means of the coiled spring 118. With such a construction, wherein the cutter carrying heads are held yieldingly against the sides of the shoe, there is a danger that the knives will 65 be displaced from their proper relation to

the welt. A locking device is, therefore, provided which, during the inward movement of the heads, operates to lock them against any outward movement and, after the heads have been finally placed at the 70 limit of their inward movement, holds them firmly in this position. The preferred form of the locking device is best shown in Figs. 8, 13, and 20 to 22. The cam lever 110, which is operated by the cam C⁵ to open the cutter carrying heads, is provided at its upper end with a rearwardly and upwardly extending plate 230 (Fig. 6) provided at its rear with a pin 231. At its upper edge this plate is provided with a latch 232 having a rounded forward hook end and pivoted at its rear end upon a pin 233 for movement in a substantially horizontal plane. This latch is held yieldingly against outward movement by a leaf spring 234 secured to the 80 side of the plate. The hook end of the latch is thus permitted an outward movement when its rounded end engages an obstruction. It is normally maintained in the position shown in Fig. 6 by the spring 234. 85 The right hand bearing for the stud 196, viewing Figs. 3 and 8, is provided with a rearwardly projecting casting 236 (Fig. 22) having at its upper end a lug carrying a horizontal pin 237 upon which there is 90 loosely pivoted a bell-crank lever having a hook-ended rearwardly extending arm 238 and a depending arm 239 provided at its lower end with a pin 240. The bell-crank lever is normally held in engagement with 95 a conveniently arranged stop pin by a suitably connected spring 235 (see Fig. 22). The pin 240 is adapted to be engaged by the hooked latch 232 on the plate 230. The casting 236 is also provided with a central 100 boss carrying a horizontal pin 241 (Fig. 22) on which is loosely pivoted a plate 242 having a cam surface 243 adapted, when the plate is in its lower location (see Fig. 13), to engage the pin 231 in the plate 230. The plate 242 is provided at its upper edge, in 105 the rear of the latch 232, with a pin 244 which projects from both faces of the plate. The end of this pin projecting from the left hand side of the plate 242 (viewing Fig. 8) is adapted to be engaged by a hook 245 (Figs. 13 and 21) at the lower end of an arm loosely pivoted at its upper end on a pin 246 projecting from the bent arm 194 of the bell-crank lever which supports the cam head 192 for actuating the hammer. An inspection of Fig. 8 will show that the hook 245 is so located that it can engage the end of the pin 244 which projects from 110 the right hand side of the cam plate 242. 115

Assuming now that the cutter carrying heads are open and are about to be closed, the mechanism just described operates to lock the heads against outward movement in the following manner: At this time the 120 125 130

hammer is raised and, therefore, the cam head 192 is in the position shown in Fig. 21 ready to release the hammer upon a slight backward movement. During the forward movement, as heretofore described, of the cam head, the hook 245 has engaged and lifted the cam plate and placed the pin 244 under the hook-ended bell-crank arm 238 (see Fig. 20). While these parts are engaged the cam plate 242 is held raised above the path of movement of the pin 231 in the plate 230. At this time the upper end of the lever 110 is in its forward position and, therefore, the plate 230 is in its forward position and the latch 232 is out of contact with the pin 240 on the bell-crank arm 239. As soon, however, as the cam C⁵ permits the lever 110 to move rearwardly, under the action of the springs 118, the latch 232 engages the pin 240 and moves the bell-crank 239 about its pivot in a direction to release the pin 244 and permit the cam plate 242 to drop down, by gravity, about its pivot 241 (see Fig. 21). The cam plate 25 is thus placed in front of the pin 231 (see Fig. 13) and forms a rigid strut between the lever 110 and the machine frame. While the cam plate is in this position no forward movement can be imparted to the lever 110, and, therefore, the cutter carrying heads cannot be opened. The continued rearward movement of the lever 110 permits the cam 242 to drop farther and farther, thus wedging itself between the pin 231 and the casting 236 upon which it is mounted. Of course, the cutter carrying heads advance varying distances, according to the width of the shoe being operated upon, but the form of lock just described provides for a retention of the heads in whatever inward position they may assume. After the welt has been butted, the first operation is to raise the hammer, which is done, as already described, by the forward and then rearward movement of the cam head 192. The cam plate 242 is simultaneously raised by the hook 245. The lever 110 is now free to move forward to move the cutter carrying heads outward as the cam plate 242 has been removed from its locking position. During the backward movement of the cam head 192, to position it for the release of the hammer, the hook 245 drops away from the pin 244 to a position where the cam plate is permitted to fall by gravity into locking position upon the next inward movement of the cutter carrying heads (see Fig. 21).

It is obvious that in order to sever the welt squarely and evenly the welt ends 60 should be laid flat in advance of the welt butting cutters. The welt is ordinarily in temper when it is secured to the upper and insole by the welter, and, therefore, when the shoe comes to the welt butting machine, 65 it is frequently found that the end of the

welt has dried in a position curled or bent up, or down, so that it is impossible to cut it squarely and evenly unless it is first smoothed out. In Figs. 23, 24 and 25 the machine has been shown as provided with a 70 welt pressing attachment, acting in advance of each of the welt butting cutters, for smoothing out the welt prior to the operation of said cutters. This presser is the same for each of heads H and H¹ and is 75 shown as comprising a head 250 mounted upon a shank which is pivoted at 251 upon a horizontal pin projecting from a block 252 loosely pivoted upon a vertical pin 253 carried at the rear of the welt butting cutter carrier 128. The purpose of the double pivoting of the welt presser will be presently explained. A spring 254 is secured by one end to an ear projecting upwardly from the shank of the presser and by its other end to 80 a stationary part of the cutter carrying head so that the presser is normally maintained yieldingly pressed downwardly against the welt. A stop pin 255 projecting from the face of the welt butting cutter carrier limits 85 the downward movement of the presser. The presser head 250 is mounted just in advance of the welt butting cutter and the strength of the spring 254 is sufficient to cause it to smooth out the welt and lay it 90 evenly in front of the cutter for the butting operation.

It frequently happens that when the welt dries after having been in temper, its free end projects outwardly at quite an angle 100 from the sides of the last, and although the welt locators 30, by bearing on the ends of the inseam, will, to some extent, force this free end of the welt in over the insole, their point of operation is not such as to be able 105 to bring it completely in. It is, therefore, desirable to provide means to move the free ends of the welt inward so that the entire welt end will be in alinement with the stroke of the welt butting cutters. To gain this 110 end the welt presser head 250 is provided at its outer side with a depending lip, or welt edge guide 256 (Figs. 29 and 30) which, when the presser itself is in engagement with the face of the welt, is in engagement with 115 the outer edge of the welt. The purpose of the vertical pivot pin 253 is to permit the spring 254, which is diagonally arranged (see Fig. 25), normally to maintain the welt edge guide 256 away from the welt by turning the welt presser about the pivot pin as a center. As the welt butting cutter carrier is retracted within the cutter carrying head, a boss 257 on the inner side of the shank of the presser engages a cam plate 120 258 on the face plate 100 of the cutter carrying head and the presser is moved inward by this means to a position where the welt edge guide will, by its engagement with the outer edge of the welt, maintain the welt end in 125 130

proper butting relation to the welt butting cutters. The cam plate 258 is so designed that after the welt edge guide has been brought to the lateral position just described, it is permitted to be carried rearwardly with the welt butting cutter carrier in the line of travel of the cutter, therefore, if the welt end projects outwardly over the side of the last it will be engaged at its edge by the welt guide 256 and will throughout the entire welt butting stroke of the cutter be forced, if necessary, inwardly over the insole to a position for proper severance. When, during the stroke of the welt butting cutter, the presser 250 reaches the cutting block 152, the spring 254 yields and permits the presser to rise about its pivot pin 251 and ride up and over the cutting block. Thereafter, when the cutting block itself moves upwardly about its pivot pin 148, the spring 254 yields still further and permits the presser 250 to rise with the cutting block. When the welt butting cutter is again moved forwardly within the cutter carrying head, the presser is moved downwardly by the spring 254 to the level determined by the stop pin 255 and is also moved outwardly by the same spring to a position with its welt edge guide out of engagement with the edge of the welt.

Although the operation of the various separate mechanisms of the machine has been described in detail in connection with the detailed description of the preferred embodiment, nevertheless a brief résumé of the operation of the machine as a whole will assist in an understanding of its construction. When the machine is at rest the toggle 61, 62, which supports the welt locators, is broken and the welt locators are in their lowered position as shown in Fig. 10. The cutter carrying heads H and H^1 are open, or in their outward locations, and this position of the heads has also carried the welt locator supporting arms L and L^1 outward. While these parts are in this position a shoe may readily be placed against the shoe rest without its upper being marred by an engagement with some of the working parts. The forepart of the hammer D is raised, holding the drivers 92 in the position shown in Fig. 7, they being at this time at the outer ends of the bail 174 at the head of the hammer owing to the outward positions of the cutter carrying heads. The throat plates 96 are also raised, as shown in Figs. 7 and 10, out of the path of movement of the welt butting cutters. The welt butting cutter carriers are held raised about their pivots 126 by the springs 132, as shown in Fig. 10. The cutting blocks 152 are held in their recesses 158, in the lower sides of the welt butting cutter actuators 120, by the springs 156, the actuators 120 being at this time at the forward end of their stroke, as

shown in Fig. 10. The locking cam plate 242 for the cutter carrying heads is held in its raised, or released, position about its pivot 241 by an engagement of the hook arm 238 with the pin 244, as in Fig. 20. The cam head 192 is above the roll 183 on the rear part of the hammer but is in a position to release the hammer upon a slight rearward movement (Fig. 21).

Upon depressing the starting treadle, the first actuating cam to become active is the groove cam C^1 which controls the operation of the welt locators. The welt locators are, by this cam, first moved inward about their pivots 32 and then upward about their pivots 36 into contact with the under, or grain side, of the welt and to a position opposite the welt crease ready to be thrust into the welt crease by the inward movement of the cutter carrying heads. The next cam to become active is the cam C^5 which permits the cutter carrying heads to be moved inwardly, laterally, under the action of their springs 218. The inward movement of the heads moves the cam lever 110 rearwardly about its pivot 112, thus causing an engagement of the hooked latch 232 with the pin 240 on the bell-crank arm 239 and releasing the locking cam plate 242 so that it falls by gravity, its cam surface 243 engaging the pin 231 upon the plate 230 at the upper end of the cam lever. As the cutter carrying heads move farther inward and the cam lever moves farther backward the locking cam plate is permitted to move farther downward, thus holding the cutter carrying heads from outward movement and locking them in whatever inward position they may assume. The extent of inward movement is, of course, determined by the width of shoe being operated upon. As the cutter carrying heads approach the limit of their inward movement, the beveled lugs 80 thereon engage the beveled lugs 82 on the welt locators and the welt locators are forced into, and to the bottom of, the welt crease until the blades 29 engage the inseam. Further inward movement of the heads at this time, under the action of the springs 218, causes the welt locators to tighten and stretch the upper at the ends of the inseam and to move the welt ends inward over the insole until they lie in the path of travel of the welt butting cutters. The welt butting cutters are simultaneously placed in a position over the welt. The tension of the springs 118 has been preliminarily adjusted by means of the nuts threaded on the ends of the rod 116 so that the force which can be exerted inward on the inseam is not greater than the strength of the materials upon which the welt locator blades bear. Thus, no greater pressure is placed upon the inseam than it can stand although a sufficient pressure will be used to 130

enable the blades 29 to tighten the upper and place the welt in proper butting position.

After the cutter carrying heads have been moved inward and have placed the welt 5 butting cutters above the welt and the welt has been moved inward over the insole into alinement with the stroke of these cutters, the groove cam C⁴ becomes active to turn the cam lever 136 rearwardly about its pivot 10 188 and draw the welt butting cutter actuators 120 rearwardly within the cutter carrying heads. This movement is continuous and acts first to place the welt butting cutters in contact with the upper or flesh side 15 of the welt (see Fig. 27) and thereafter sever the welt with a beveled cut (see dotted lines Fig. 27). During the stroke of the welt butting cutters the cutting blocks 152 are moved inward by the cam plates 166 20 mounted upon the welt butting cutter actuators and the stitch cutters 168, on these cutting blocks, enter the welt crease and sever the stitches in the rear of the point at which the welt is to be butted. If the welt 25 pressers 250 and the welt edge guides 256 are being used, these parts are also moved inward at this time assisting, in the manner described, in preparing the welt for the operation of the welt butting cutters. After 30 the welt has been severed, the cam C⁴ causes the welt butting cutter actuators to continue their rearward movement and the welt butting cutters advance, beneath the cutting block 152, to a position beyond the end of 35 the butted welt as shown in Figs. 13, 14 and 28. This continued movement of the welt butting cutters enables them to level off the heel seat in the manner described. During this continued rearward movement of the welt butting 40 cutters, the cam C⁶ is operating to lower the throat plates 96 to a position above the scarfs just formed upon the welt ends by the welt butting cutters and in alinement with the drivers 92. As soon as the throat 45 plates have reached this position, the groove cam C³ actuates the cam head 192 rearwardly and releases the hammer D. The hammer descends under the action of its driving spring 188 and the drivers in 50 their descent separate tacks from the race- ways 94 and drive them through the beveled welt ends and into the insole. This operation secures the beveled welt ends in the position in which they have been placed by 55 the welt locators and in addition secures the tightened upper to the insole. As hereinbefore described a fastener inserted at this point completes the line of fasteners from the end of the inseam to the heel seat tacks. 60 The operations on the shoe having been completed, the various actuating cams now operate, first, to move the cam head 192 forwardly and then rearwardly to raise the hammer D. This movement of the cam head

192 raises the cutter carrying head locking 65 plate 242 (see Fig. 20) and releases the cutter carrying heads. The raising of the hammer D raises the drivers 92 out of the throat plates 96. When these throat plates have been thus freed they are raised by a movement about their pivots 212. The welt butting cutter actuators 120 now move forward within the cutter carrying heads. This permits the welt butting cutter carriers to be moved forward and upward by the springs 70 132 and the cutting blocks 158 to be moved outward, into the recesses formed for their reception, by the springs 156. The knives being now clear of the work, the cutter carrying heads are opened and the welt locators 75 80 are moved outward by the heads and are then dropped away from the welt. The forward movement of the cam lever 100 forces the hooked latch 232 past the bell-crank pin 240 placing it in position to trip the bell-crank when the heads are again closed. All 85 of the working parts being now clear of the shoe, it can safely be removed from the machine.

While the invention has been described 90 and shown as embodied, and is preferably embodied, in a machine for operating upon both free ends of the welt simultaneously, it will be apparent that many features of the invention may be embodied in a machine arranged to operate upon only one side of the shoe at a time. The position of the work with the bottom of the shoe upward is considered the most convenient position and the machine is, therefore, arranged to operate upon a shoe in this position. It will be understood, however, that the machine may be arranged to operate upon a shoe held in any position and where in the claims the relative positions and movements of the 100 parts have been defined with respect to a shoe held in this position, it will be understood that it is not intended thereby to limit the invention to this particular position of the work but that the claims intend merely to 105 describe in a convenient manner the position and movement of the parts with relation to the shoe and regardless of the position of the latter.

Nothing herein contained is to be interpreted as limiting this invention in the scope of its application to use in connection with the particular machine or the particular mode of operation, or both, herein illustrated and described. While the particulars 115 of construction herein set forth are well suited to one mechanical form of the invention, it is not to be understood that these particulars are essential since they may be variously modified within the skill of the 120 artisan without departing from the true scope of the actual invention as defined in the following claims.

What is claimed as new, is:—

1. A welt butting machine, having, in combination, welt locating, welt butting and welt fastening devices, and means affording provision for operating said devices successively in the sequence named, substantially as described. 70
2. A welt butting machine, having, in combination, welt locating, stitch cutting, welt butting and welt fastening devices, and means for operating said devices, substantially as described. 75
3. A welt butting machine, having, in combination, separately mounted welt locating, butting and fastening devices, and independent actuating means for operating each of said devices, substantially as described. 80
4. A welt butting machine, having, in combination, welt locating, welt butting and welt fastening devices normally held withdrawn from the work, and means affording provision for bringing said devices into operative position at different times, substantially as described. 85
5. A welt butting machine, having, in combination, devices engaging the welt crease to force the welt end inward over the insole into cutting position, welt butting cutters, means for operating said cutters, and a tacking device operating to drive a tack through the butted welt end to secure it to the insole, substantially as described. 90
6. A welt butting machine, having, in combination, welt locating and welt butting devices, and a tacking device comprising a driver, a throat plate normally removed from operative position, means to supply tacks singly to the throat plate, and actuating means for said parts operating to place the throat plate in operative position, deliver a tack thereto and drive said tack, substantially as described. 95
7. A welt butting machine, having, in combination, welt butting cutters, automatically operating devices for finding and locating the welt in butting position relatively to the cutters, means for operating said cutters to butt the welt, and means for tacking the located and butted welt to the insole, substantially as described. 105
8. A welt butting machine, having, in combination, a shoe rest for supporting a shoe sole up, vertically and laterally movable welt locators at the sides of the shoe operating in the welt crease, longitudinally movable welt butting cutters above the shoe, and tacking devices above the shoe constructed and arranged to operate in the rear of the welt butting cutters, substantially as described. 110
9. A welt butting machine, having, in combination, a tack driver opposite the portion of the welt which is to be butted, a throat plate between the driver and the welt, means to supply tacks thereto, a welt butting cutter operating between the driver and welt, and means to remove the throat plate from its operative position to permit the cutter to operate, substantially as described. 115
10. A welt butting machine, having, in combination, welt locating, welt butting and welt fastening devices, and automatic operating means therefor, substantially as described. 120
11. A welt butting machine, having, in combination, a welt locator normally withdrawn from the welt, means to cause said locator to find and engage the grain side of the welt, and separate means to force the welt locator into the bottom of the welt crease, substantially as described. 125
12. A welt butting machine, having, in combination, means to support a shoe sole up, a welt locator below the welt comprising a welt engaging plate, means for moving said plate inward into contact with the counter of the shoe and then toward the welt and into contact with its underside and separate means for thereafter forcing said plate into the bottom of the welt crease, substantially as described. 130
13. A welt butting machine, having, in combination, a welt butting cutter, a welt support coöperating with said cutter to form a beveled cut, and means for moving said parts relatively to each other laterally, substantially as described. 135
14. A welt butting machine, having, in combination, a welt butting cutter movable toward and from the shoe, and a welt support coöperating with the cutter and movable toward and from the shoe independently of the cutter movement, substantially as described. 140
15. A welt butting machine, having, in combination, means to support a shoe sole up, a laterally movable welt support adapted to engage the underside of the welt, and an independently mounted, laterally movable welt butting cutter above said welt support and coöperating therewith to form a beveled cut, substantially as described. 145
16. A welt butting machine, having, in combination, a welt locator at each side of the shoe mounted to move inwardly into contact with the counter and toward and into engagement with the grain side of the welt, and a single actuating means for moving said locators in the sequence of directions named, substantially as described. 150
17. A welt butting machine, having, in combination, a pair of welt locators one at each side of the shoe and mounted to swing about both vertical and horizontal axes, a cam, and an actuating train operated by the cam affording provision for a movement of the locators about their vertical axes prior to a movement about their horizontal axes, substantially as described. 155

18. A welt butting machine, having, in combination, a laterally movable head at each side of the shoe, welt butting devices sustained by said heads, and a welt locator 5 at each side of the shoe, for placing the welt ends in butting position, laterally movable independently of the heads, substantially as described.
19. A welt butting machine, having, in combination, laterally swinging heads at each side of the shoe, welt butting cutters sustained thereby, laterally swinging welt locators at each side of the shoe, and separate actuating means for placing said welt butting cutters and welt locators in operative position relatively to the welt, substantially as described.
20. A welt butting machine, having, in combination, a shoe rest for supporting the 20 shoe sole up, a welt support operating below the welt, a cutter operating above the welt, both of said parts being normally withdrawn from the welt, and separate actuating means for placing said parts in operative 25 position, substantially as described.
21. A welt butting machine, having, in combination, a laterally swinging head at each side of the shoe, welt cutters carried thereby, a laterally swinging arm sustaining 30 a welt support at each side of the shoe, and automatic means to move said welt supports into operative position at one side of the welt and thereafter to move said welt cutters into operative position at the other side 35 of the welt, substantially as described.
22. A welt butting machine, having, in combination, a laterally movable welt locator at each side of the shoe, means for causing said locators to find and engage in 40 the welt crease, a laterally movable cutter carrying head at each side of the shoe, actuating means therefor, and devices on said heads for engaging said welt locators to force them into the welt crease in advance 45 of the heads, substantially as described.
23. A welt butting machine, having, in combination, a welt support adapted to engage in the welt crease and mounted for movement toward and from the bottom of 50 the shoe, a cutter carrying head at the opposite side of the welt, and means on the head for engaging the welt support and controlling its position relatively to the plane of the bottom of the shoe, substantially as de- 55 scribed.
24. A welt butting machine, having, in combination, a cutter carrying head and a relatively movable welt support both normally removed from operating position, 60 means to move said parts separately into operative position, and means for locking said parts against relative movement vertically while in operating position, substantially as described.
- 65 25. A welt butting machine, having, in combination, a welt support below the welt, a laterally movable head sustaining a welt butting cutter above the welt, and locking means between the welt support and head and controlled by the lateral movement of 70 the head for determining the vertical relation of the welt butting cutter to the welt support, substantially as described.
26. A welt butting machine, having, in combination, a vertically movable welt support adapted to engage in the welt crease, a lug having a beveled side sustained by said support, a laterally movable cutter carrying head at the opposite side of the welt, and a lug having a complementary beveled side sustained by said head, the beveled sides of said lugs being arranged to engage each other as the head moves laterally and cause an adjustment of the welt support vertically relatively to the face of the welt, substantially 80 as described.
27. A welt butting machine, having, in combination, a welt locator, a stitch cutter, a welt butting cutter, and actuating means for said parts constructed and arranged to 85 operate them at substantially the same point in succession and in the sequence named, substantially as described.
28. A welt butting machine, having, in combination, a welt locator, a stitch cutter, 90 a welt butting cutter, an actuator for said welt locator, and a separate actuator for said stitch and welt butting cutters, substantially as described.
29. A welt butting machine, having, in 100 combination, a welt butting cutter, an independently-mounted stitch cutter, and a single means for operating both of said cutters, substantially as described.
30. A welt butting machine, having, in 105 combination, a welt butting cutter, a stitch cutter, means for operating the welt butting cutter, and means for operating the stitch cutter controlled by the movement of the welt butting cutter, substantially as de- 110 scribed.
31. A welt butting machine, having, in combination, a stitch cutter movable across the shoe, a welt butting cutter movable longitudinally of the shoe, means for actuating 115 the welt butting cutter, and means for transmitting movement to the stitch cutter from the welt butting cutter, substantially as described.
32. A welt butting machine, having, in 120 combination, a longitudinally movable cutter carriage, a welt butting cutter thereon, a transversely swinging cutter carriage, a stitch cutter thereon, and a cam plate on the first named cutter carriage arranged to engage the latter named cutter carriage and move the stitch cutter transversely as the welt butting cutter moves longitudinally, 125 substantially as described.
33. A welt butting machine, having, in 130

combination, a welt butting cutter, a stitch cutter mounted for movement both horizontally and vertically relatively to the welt butting cutter, and means affording provision for operating said cutters, substantially as described.

34. A welt butting machine, having, in combination, a welt butting cutter above the welt, a stitch cutter at the side of the shoe 10 mounted to move inward into the line of cut of the welt butting cutter to coöperate therewith in forming the cut, and upward to permit the welt butting cutter to pass beneath it after the cut is made, and actuating means 15 for said cutters, substantially as described.

35. A welt butting machine, having, in combination, a longitudinally movable welt butting cutter, a stitch cutter normally withdrawn from the welt and movable 20 transversely both into and out of stitch cutting position during the movement of the welt butting cutter, and means for moving said cutters in the directions named, substantially as described.

36. A welt butting machine, having, in combination, a stitch cutter, a welt butting cutter and a welt tacker all normally withdrawn from the welt, and means for causing 30 said parts to operate on the welt end successively in the sequence named, substantially as described.

37. A welt butting machine, having, in combination, welt butting devices, welt securing devices, and means affording provision for operating the welt securing devices upon the same portion of the welt as the welt butting devices operate upon, substantially as described.

38. A welt butting machine, having, in combination, a welt butting cutter, a tacker, and means affording provision for operating said parts successively upon the same portion of the welt, substantially as described.

39. A welt butting machine, having, in combination, means for beveling the welt end, and means for inserting a fastener through the extremity of the bevel so formed, substantially as described.

40. A welt butting machine, having, in combination, a welt butting cutter operating to bevel the welt end, and means for driving a tack through the bevel so formed while the shoe remains in welt butting position, substantially as described.

41. A welt butting machine, having, in combination, a welt butting cutter operating to bevel the welt end, a tacker throat normally removed from the welt, means for moving said cutter off of the bevel and said throat on to the bevel, and means for inserting a tack in the welt, substantially as described.

42. A welt butting machine, having, in combination, a welt butting cutter, welt end

securing means including a tack hopper, a raceway and a movable tacker throat normally withdrawn from the welt, and a single means for supplying said raceway with tacks and for placing said throat in tack driving position over the butted welt end, substantially as described.

43. A welt butting machine, having, in combination, laterally movable heads at each side of the shoe, stitch cutters movable inwardly relatively to the heads mounted in said heads, means for operating said cutters, and means for locking said heads against outward movement during the operation of the stitch cutters, substantially as described.

44. A welt butting machine, having, in combination, laterally movable heads carrying welt butting and securing devices yieldingly held against each side of the shoe, means for operating said devices, and a locking device to hold the heads rigidly against movement during the operation of said welt butting and securing devices, substantially as described.

45. A welt butting machine, having, in combination, laterally movable heads carrying welt butting and tacking devices including a tack driver yieldingly held against each side of the shoe, means for withdrawing the tack driver preparatory to inserting a tack, and a locking device operated by said tack driver withdrawing means for holding said heads against outward movement until the welt has been secured, substantially as described.

46. A welt butting machine, having, in combination, a welt butting cutter, a stitch cutter, means for operating said cutters, and a welt support mounted independently of both of said cutters, substantially as described.

47. A welt butting machine, having, in combination, a welt butting cutter, an angularly adjustable welt support, and a stitch cutter mounted to permit an adjustment of the welt support without disturbing the relation of the stitch cutter to the inseam, substantially as described.

48. A welt butting machine, having, in combination, a welt butting cutter, actuating means therefor, a device to engage the edge of the free end of the welt and move it into butting position across the shoe relatively to the insole and upper, and provision for operating said device, substantially as described.

49. A welt butting machine, having, in combination, a welt butting cutter, actuating means therefor, and a welt edge guide movable with and in advance of the cutting edge of the cutter to position the welt for the action of the cutter, substantially as described.

50. A machine for butting welts, having, in combination, a welt butting cutter, means to move said cutter toward the heel of the shoe to butt the welt, a welt presser constructed and arranged to move with and in advance of the cutting edge of the welt cutter, and a welt edge guide movable with the welt presser, substantially as described. 65
51. A welt butting machine, having, in combination, a welt butting cutter, actuating means therefor, and a welt presser mounted for movement in the line of cut in advance of the cutter and provided with an outer lip for engaging the edge of the 70 welt to move the welt inward and position it for the action of the cutter, substantially as described. 75
52. A welt butting machine, having, in combination, a welt butting cutter, actuating means therefor, a welt edge guide normally removed from the welt, and provision for imparting to said guide a movement across the shoe to engage and position the welt and thereafter a movement in the 80 line of cut to hold the welt in position during the cut, substantially as described. 85
53. A welt butting machine, having, in combination, a welt butting cutter, actuating means therefor, a welt presser bearing on the flesh side of the welt and having a projecting lip to engage the edge of the welt, and means for causing said lip to engage the edge of the free end of the welt and move it across the shoe into butting position and thereafter maintain it in such position for the action of the cutter, substantially as described. 90
54. A welt butting machine, having, in combination, a welt butting cutter, actuating means therefor, a welt presser, and means to move the welt presser first across the welt to a position in front of the knife and thereafter in the line of cut, substantially as described. 95
55. A welt butting machine, having, in combination, a welt locator acting in the welt crease to tighten the upper and move the welt inward adjacent the end of the inseam, a welt edge guide to act on the free end of the welt and move it inward, and a welt butting cutter to sever the welt after it has been acted on by said welt locator and welt guide, substantially as described. 105
56. A machine of the class described, having, in combination, means for positioning the butt end portion of the welt of a lasted and welted shoe, means for butting the welt, and means for inserting a tack relatively to the welt while the welt is held by 110 said positioning means. 115
57. A machine of the class described, having, in combination, means for positioning the butt end portion of the welt of a lasted and welted shoe, means for butting the 120 welt, means for pressing the welt end inwardly, and means for inserting a tack adjacent to the welt end while the pressure is maintained. 125
58. A machine of the class described, having, in combination, means for butting simultaneously the two ends of the welt of a lasted and welted shoe, means for tacking the welt ends, means for positioning the welt ends for the butting and tacking operations, and an additional device for positioning the shoe during said operations. 80
59. A machine of the class described, having, in combination, a shoe positioning device, means for positioning the butt end portion of a welt of a lasted and welted shoe, means for butting the welt, and means for inserting a tack relatively to the welt while the welt is held by said positioning means. 85
60. A machine of the class described, having in combination, cutting means constructed and arranged to bevel a welt and cut stitches which may connect the butt end of the welt to the shoe, and means for actuating said cutting means to perform the two operations at the same time. 90
61. A machine of the class described, having in combination, a knife for cutting the inseam, means for actuating the knife, a guard, and means for moving the guard transversely of the shoe bottom toward and from operative position to protect the upper 100 from injury by the knife. 95
62. A machine of the class described, having in combination, a knife for cutting the inseam stitches at the butt end of a welt, means for actuating the knife transversely of the shoe bottom, and a guard to enter the welt crease for protecting the upper from injury by the knife. 105
63. A machine of the class described, having means for butting a welt, and devices movable transversely of the shoe and relatively to the butting means for positioning the welt relatively to the butting means. 110
64. A machine of the class described, having means for engaging a shoe in the welt crease, a welt butting cutter, and actuating mechanism for causing the engaging means to tighten the upper over the last and hold it under tension while the welt is butted and the upper fastened. 115
65. A machine of the class herein described, having in combination, means for butting a welt, means for pressing the welt end inwardly, and means for inserting a tack adjacent to the welt end while the pressure is maintained. 120
66. A machine of the class herein described, having in combination, means for

butting the opposite ends of a welt simultaneously, means for engaging the welt crease laterally to press the welt end inwardly, and means to fasten the shoe stock while the welt is so pressed inwardly.

67. A machine of the class herein described, having in combination, rests for the two ends of the welt of a welted shoe, co-operating cutters, and a welt end tacker.

68. A machine of the class herein described, having in combination, means for butting a welt, means for tightening the upper over the last bottom adjacent to the end of the welt, and means for tacking the upper.

69. A machine of the class herein described, having in combination, means for butting a welt, means for tightening the upper over the last bottom in the region of the welt end, and a tacker adapted to fasten the upper and the welt end.

70. A machine of the class described, having in combination, stitch cutting means, welt butting means, upper tightening means and tacking means.

71. A machine of the class described, having in combination, stitch cutting means, welt butting means, welt butt holding down means, upper tightening means, and tacking means.

72. A machine of the class described, having in combination, a cutter to sever the inseam stitches, a blade to tighten the upper, and a tacker to fasten the upper.

73. A machine of the class described, having in combination, a cutter to sever the inseam stitches, a cutter to butt the welt, and a tacker to fasten the welt end.

74. A machine of the class described, having in combination, a cutter to sever the inseam stitches, a cutter to butt the welt, a

blade to tighten the upper, and a tacker to fasten the upper.

75. A welt butting machine having, in combination, a welt butting cutter, a welt support co-operating with said cutter to form a beveled cut, and means for moving said cutter laterally, relatively to the welt support, into cutting position, substantially as described.

76. A machine for butting welts having, in combination, two swinging heads on opposite sides of the machine, a cutter plate mounted in each head adapted to be inserted in the welt crease, two other swinging heads, one above each of the cutter plate carrying heads, a tacker mechanism mounted in each of said other swinging heads, means for moving the cutter plate heads inward, separate means for moving the tacker heads inward, and provision for controlling the inner position of the tacker heads from the inner position of the cutter plate heads, substantially as described.

77. A machine for butting welts, having, in combination, two swinging heads on opposite sides of the machine, means for holding a shoe in position between said heads, a tacker mechanism mounted in each of said heads, means for swinging the heads inward and outward toward and from the shoe, and means controlling their inward movement by virtue of which they are invariably brought to rest with the tacker mechanism in position to drive a tack through the welt whatever the width of shoe being operated upon, substantially as described.
